UNITED STATES PATENT OFFICE.

JONAS HETLAND AND MARCUS HETLAND, OF VALLEY CITY, NORTH DAKOTA.

PLOWSHARE.

1,425,012.

Specification of Letters Patent. Patented Aug. 8, 1922.

Application filed May 6, 1921. Serial No. 467,451.

To all whom it may concern:

Be it known that we, JONAS HETLAND and MARCUS HETLAND, citizens of the United States, residing at Valley City, in the county 5 of Barnes and State of North Dakota, have invented new and useful Improvements in Plowshares, of which the following is a specification.

The present invention relates, in general, 10 to plows, and is especially directed to that type of plows having a removable share.

The essential features of the invention consist of a plow share member provided with means adapted, in conjunction with 15 means positioned on a frog associated with such share, to maintain the share in operative relation, and means to securely lock the share against accidental disengagement.

The object of the invention is to provide a 20 construction having a removable share member adapted to be quickly and conveniently attached to the frog, and which may be removed therefrom by hitting the rear end of the share a slight blow with any handy implement, the arrangement and assemblage of 25 the parts being such that in use the tendency is for parts always to bind and tighten so that, while they may be readily disassembled for replacement or repair, all danger of accidental separation of the parts while in use 30 is eliminated.

We accomplish this object by providing a share member with means adapted to engage a plurality of keyhole slots arranged in the 35 frog and having flaring and tapered sides and ribs thereon to receive the share member engaging means here shown as attached to the inner face of the plow share, the arrangement of securing means being such as 40 to tend to lock the share to the frog under normal operative conditions of use of the plow.

The structure which will now be described in detail comprises few and simple parts 45 which can be readily secured together by simple and effective means, so as to present all the advantages of a one-piece plow, and at the same time be readily disassembled from locked relation to permit the share 50 or other parts to be replaced. This ready assembling and disassembling of the parts is desirable for the reason that the expense and time incident to reshaping and sharpening the plow is done away with, and the worn 55 share member may be removed and replaced by a new member which can be furnished at

small expense by the farmer without the necessity of employing skilled labor to effect the repair, and without the loss of time incident to reshaping and sharpening a worn 60 plow.

The objects and advantages of our invention will be apparent from the following description, taken in connection with the drawings, and it will be understood that such 65 changes and modifications in the specific structure shown and described that may come within the scope of the appended claims may be made without departing or exceeding the spirit of the invention. 70

Figure 1 is a top plan view of the plow;

Figures 2 and 3 are side elevational views looking in the direction of the land side and mold board respectively;

Figure 4 is a bottom perspective view 75 showing the frog secured to the land side and mold board;

Figure 5 is a detail view of the frog detached;

Figure 6 is a detail view of the share member 80 detached from the plow;

Figure 7 is a sectional plan view of the front end of the plow share removed;

Figure 8 is a detail view of the keyhole slot and a lug securing means; 85

Figure 9 is a section of Figure 6 taken on the line 9—9;

Figure 10 is a detail section on the line 10—10 of Figure 8.

Referring to the drawings, wherein like 90 letters indicate similar parts, 10 designates a frog member comprising a mold board portion 11, and a land side portion 12 having a reduced portion 13 extending to the forward end of the plow and forming, with the member 11, the point 14. A mold board 15 and a landside 16, which may be integrally formed, are secured to the frog by means of the apertures 17 formed in the frog member 10, through which pass the threaded 100 bolts 18 which secure the mold board and the landside to the frog, suitable securing bolts 19 and washers 20 being provided by which the mold board is secured to the mold board portion 11 of the frog 10. 105

A plurality of keyhole slots 21 are arranged in the mold board portion 11 of the frog 10, said slots having flaring and tapered sides 22 which form sunken rib members 23. The removable share member 24 having an 110 elongated portion 25 and a base portion 26 has a series of lugs 27 attached to the inner

side of the elongated member 25, said lugs being adapted to fit in the flaring and tapered keyhole slots 21 on the frog 10. The forward portion 24 of the share has a recess 28 for the reception of the point 14 of the frog, a flange 29 arranged on the underside of the base member 26 tends to hold the point 14 of the frog in position, and also forms at its end a tenon 30 which fits a corresponding member 31 located at the forward end of the landside 16.

The share, when attached to the plow, has its elongated member 25 so arranged as to form a continuation of the mold board 15, while the base member 26 lies in longitudinal alignment with, and forms a continuation of the landside 16, the reduced portion 13 of the frog being so cut away as to allow the base 26 to abut against a shoulder 32 on the member 12, thus allowing the plow share to form an extension of and be backed up by the landside 16.

It will be observed that with this construction, the mold board and landside and the frog are coupled by the bolts, as heretofore described, and that the plow point and share member are so connected to the frog and assembled with the other parts by means of the keyhole and tapered slots and the headed studs referred to, that plowing pressure upon the point and forward share member tends always to tighten the removable share member and hold it in place. By pocketing the lower end of the share member and engaging that pocketed end with and backing it up by the point of the frog, as described, shearing or breaking strains on the studs which engage the keyhole slot are eliminated, and the assembled parts are firmly interlocked. Removal of the share member may, however, be readily accomplished by striking the share member at its rear end, driving the headed studs out of the keyhole slots and the pocketed point off of the frog point, as will be clear from consideration of Figs. 3 and 4.

It will be understood that such changes from the specific disclosure as are within

the range of mechanical skill may be made without departing from the spirit of the invention.

We claim:

1. In a device of the class described, the combination of a mold board and land side having a shouldered recess on its under side, a frog having one of its sides provided with sunken slotted seats having stud engaging ribs which converge and are inclined upwardly towards their rear ends, and the other side formed with a forward tapered portion having a reduced shoulder thereon, a share having a rearwardly opening pocket at its forward end to receive the tapered portion of said frog, headed studs on said share to engage said sunken slots and make wedging engagement with said ribs under plowing pressure, said share member being held against relative forward movement solely by friction, so as to be readily movable to disengage said studs and pocket from the frog.

2. In a device of the class described, the combination of a mold board and land side, having a shouldered recess on its under sides, a frog having one of its sides provided with sunken slotted seats having stud engaging ribs which converge and are inclined upwardly towards their rear ends, said side extending below the edge of the mold board, and the other side formed with a forward tapered portion having a reduced shoulder thereon, a removable share having a rearwardly opening pocket at its forward ends to receive the tapered portion of said frog, and provided with horizontal and vertical flanges to abut the land side and tapered portion of said frog, headed studs on said share to engage said sunken slots in said frog and be wedged therein under plowing pressure, but readily releasable therefrom on forward movement of the share relative to said frog and mold board.

In testimony whereof we have hereunto set our hands.

JONAS HETLAND.
MARCUS HETLAND
